Primary Examiner — Catherine Ho(74) *Attorney, Agent, or Firm* — Dentons Durham Jones Pinegar(57) **CLAIM**

The ornamental design for a mattress label, as shown and described.

DESCRIPTION

FIG. 1 is a perspective view of a mattress label;
 FIG. 2 is a front view of the mattress label of FIG. 1;
 FIG. 3 is a top side view of the mattress label of FIG. 1;
 FIG. 4 is a bottom side view of the mattress label of FIG. 1;
 FIG. 5 is a left side view of the mattress label of FIG. 1;
 FIG. 6 is a right side view of the mattress label of FIG. 1;
 and,
 FIG. 7 is a rear view of the mattress label of FIG. 1.

The evenly dashed broken lines depict portions of the article that form no part of the claimed design. The dash-dot-dash broken lines define the bounds of the claimed design and form no part of the claimed design.

1 Claim, 4 Drawing Sheets(56)
